UNITED STATES PATENT OFFICE.

HEENAN SYLVESTER GOUGHNOUR, OF JOHNSTOWN, PENNSYLVANIA, ASSIGNOR TO THE LORAIN STEEL COMPANY, A CORPORATION OF PENNSYLVANIA.

SWITCH STRUCTURE.

No. 901,803.

Specification of Letters Patent.

Patented Oct. 20, 1908.

Application filed December 2, 1907. Serial No. 404,868.

To all whom it may concern:

Be it known that I, HEENAN S. GOUGHNOUR, of Johnstown, in the county of Cambria and State of Pennsylvania, have invented a new and useful Improvement in Switch Structures, of which the following is a full, clear, and exact description, reference being had to the accompanying drawings, which form a part of this specification.

10 My invention relates to certain new and useful improvements in switch structures, and is designed to provide simple and efficient means whereby the area of the supporting surface for the heel of the tongue is increased.

Another object of my invention is to provide a simple and efficient friction device for the pin or pintle of the tongue.

With these objects in view, my invention 20 consists in the novel construction, arrangement, and combination of parts as herein-after described and pointed out in the appended claims, reference being had to the accompanying drawings, in which—

25 Figure 1, is a plan view of a portion of a switch structure embodying my invention; Figs. 2 and 3, are sectional views on the lines II--II and III—III of Fig. 1 respectively; Fig. 4, is a plan view of the split bearing for the tongue pintle.

30 A, is the switch structure which is provided with the usual tread and guard surfaces. B is the tongue seat or floor of the switch structure.

35 C, is the switch tongue which is provided with the pintle c, having a countersunk or conical head c' surrounding this pintle, and within a recess D, in the floor of the switch structure, are the two portions e and e' of a 40 split bearing, the portion e being semi-circular, and the portion e' of rectangular form. The diameter of the portion e' is equal to the diameter of the rounded portion or heel of the tongue, and the thickness 45 of this split bearing is equal to the height of the pintle c.

Below the split bearing, and in the recess D, is a hard metal bearing plate E, and in front of the portion e' of the split bearing, 50 and between the tongue C and the plate E is a key or wedge F, the object of which is to clamp the pintle between the split bearing, and to hold the tongue in place.

The switch is assembled as follows:—

The plate E is dropped into the recess D, 55 and the tongue with the split bearing surrounding the pintle is dropped into its place. The tongue is clamped down on its bed and the key F is inserted into the recess D, and driven home through an opening in 60 the side of the structure. The plate E, is then raised so that it is in contact with the split bearing and the head of the pintle, after which the space surrounding the plate is filled with spelter or material of a like 65 character. The plate can be raised by various methods; either by screws projecting through the bottom of the structure, or by wedges passing through the orifices in the 70 side of the structure.

As can readily be seen by reference to the drawings, the area of the bearing surface for the heel of the tongue is greatly increased by the use of the countersunk head of the pintle, and the wear on the pintle can be 75 taken up by the use of the split bearing and the wedge. This increased bearing surface will greatly prolong the life of a switch, as it will prevent, what is known to the art as 80 the pounding down the heel of the tongue.

It will be obvious that various changes 85 may be made in the details of construction and arrangement, without departing from the spirit and scope of my invention as defined in and by the appended claims.

Having thus described my invention, what I claim as new, and desire to secure by Letters Patent is:

1. In a switch structure, a tongue having a pintle, enlarged at its free end, a split 90 bearing composed of two semicircular pieces surrounding the pintle, a recess in the switch structure to receive the pintle and split bearing, the bottom of the pintle and split bearing being on a line with each other and 95 means for tightening the bearing.

2. In a switch structure, a tongue having a pintle with a countersunk head, a split bearing composed of two semicircular pieces surrounding the pintle, a recess in the switch 100 structure to receive the pintle and split bearing, the bottom of the pintle and split bearing being on a line with each other and means to tighten the bearing.

3. In a switch structure, a tongue having a pintle, a split bearing composed of two semicircular pieces surrounding the pintle, a recess in the switch structure to receive the 105

pintle and split bearing, and a wedge to tighten the bearing.

4. In a switch structure, a tongue having a pintle with a countersunk head, a split bearing composed of two semicircular pieces surrounding the pintle, a recess in the switch structure to receive the pintle and split bearing, and a wedge to tighten the bearing.

5. In a switch structure, a tongue having a pintle, a split bearing composed of two semicircular pieces surrounding the pintle, a recess in the switch structure to receive the pintle and split bearing, the bottom of the pintle and split bearing being on a line with each other, a bearing plate for the pintle and split bearing in the recess, and means to tighten the bearing.

6. In a switch structure, a tongue having a pintle with a countersunk head, a split bearing composed of two semicircular pieces surrounding the pintle, a recess in the switch structure to receive the pintle and split bearing, a bearing plate for the pintle and

split bearing in the recess, and means to tighten the bearing.

7. In a switch structure, a tongue having a pintle, a split bearing composed of two semicircular pieces surrounding the pintle, a recess in the switch structure to receive the pintle and split bearing, a bearing plate for the pintle and split bearing in the recess, and a wedge to tighten the bearing.

8. In a switch structure, a tongue having a pintle with a countersunk head, a split bearing composed of two semicircular pieces surrounding the pintle, a recess in the switch structure to receive the pintle and split bearing, a bearing plate for the pintle and split bearing in the recess, and a wedge to tighten the bearing.

In testimony whereof, I have affixed my signature in presence of two witnesses.

HEENAN SYLVESTER GOUGHNOUR.
